UNITED STATES PATENT OFFICE.

WILLIAM H. DECKER, OF SYRACUSE, NEW YORK, ASSIGNOR TO THE SOLVAY PROCESS COMPANY, OF SYRACUSE, NEW YORK, A CORPORATION OF NEW YORK.

ART OF MAKING BILGED BARREL-BODIES.

957,457.

Specification of Letters Patent. Patented May 10, 1910.

Original application filed February 5, 1907, Serial No. 355,844. Divided and this application filed March 5, 1908. Serial No. 419,291.

To all whom it may concern:

Be it known that I, WILLIAM H. DECKER, a citizen of the United States, residing in the city of Syracuse, county of Onondaga, 5 and State of New York, have invented certain new and useful Improvements in the Art of Making Bilged Barrel-Bodies, of which the following is a specification.

My invention relates generally to the production of bilged barrel bodies, and more particularly to the making of such a barrel body made from paper pulp. Heretofore barrel bodies have been made from such pulp in the form of a cylinder, by winding the 15 same upon a cylindrical mandrel. Such barrels, however, are so inconvenient to handle on account of their shape, that their use is impracticable, except in very small sizes. Bilged barrel bodies have also been 20 made from pulp by compressing the pulp in a mold of the desired shape. Barrel bodies made in this way are, however, weak, because of the lack of cohesion between the pulp fibers, and for this reason they are undesirable as containers of heavy contents.

The object of my improvements is to obviate these objections, and provide a barrel body which, while having the lightness incident to pulp as a material and the convenience 30 of the bilged shape, shall at the same time be strong enough for any purpose for which barrels are ordinarily employed. Such a barrel body I produce in the following manner: In the first instance I lift the 35 pulp, of which the barrel body is to be formed, from a mass of such material, in a thin sheet or web having the same bilge or convexity as the barrel body which is to be formed therefrom and I so treat this web in 40 the subsequent steps of the process that it retains at all times the same shape and the same relative proportions in its several parts, until it is finally deposited in superposed layers to form the barrel body. Thus the 45 structural weakness which would result from the straining and distortion incident to a change of shape or proportion is avoided. After the web is lifted from the mass of pulp it is kept under tension either by resting 50 it on a suitably shaped rigid surface, or subjecting it to an air blast, or both, or in any other suitable manner, whereby its bilged shape is maintained, and the formation of wrinkles is prevented, until it is

finally deposited in the barrel shell. It is 55 also brought into such a position, being reversed when originally lifted with the convex side outward, that, when it reaches the bilged mandrel upon which it is eventually wound, it shall present thereto a concave 60 surface, and in this position it is moved along until it reaches the point at which it begins to take its final shape. This forward movement of the web is effected in such a manner that every point in the cross 65 section thereof progresses at a substantially uniform rate of speed from the time when it is lifted from the mass of pulp until it is finally deposited to form the barrel body. Thus, while the central longer portion of 70 the web moves more rapidly than the shorter edges, each portion maintains its original rate of speed and, by reason of the starting of the web of pulp in the bilged form, the pulp is fed to the web in such manner as to 75 meet the speed requirements of each part. By the application of the web to the mandrel upon which the barrel body is to be formed its position is again reversed so that it presents the same convex surface as when first 80 removed from the mass of pulp, and it is taken up by and wound upon the mandrel in successive superposed layers of equal thickness until the barrel body is completed. The pulp is preferably subjected to pressure 85 while being wound upon the mandrel, so that the successive layers are pressed closely together and compacted.

In the drawings filed herewith and forming a part hereof, I have indicated a form 90 of apparatus suitable for carrying this process into effect, although any suitable means may be employed for this purpose.

Figure 1 of the drawings is an end view of the apparatus; Fig. 2 is a rear elevation, 95 partly in section, with an indication of a part of the sheet of pulp being carried to and upon the forming mandrel; Fig. 3 is a side view, and Fig. 4 an end view of a completed barrel body, partly broken away 100 to show its fibrous structure.

Referring to the drawings, the bilge shaped web of pulp is lifted from the mass of pulp in a tank, A, by means of a bilge shaped roll, B, of any usual or suitable construction, such as a perforated metal shell covered with wire netting, by which the web of pulp is taken up. The roll, B, is 105

rotated by any suitable means, as the gears, b, b^2 . After the bilged shaped web has been lifted by and taken its shape upon the roll, B, it is transferred to a roll, H, the surface 5 of which presents a concavity corresponding to the convexity of the roll, B. The rolls, B and H, are placed as close together as may be without coming into actual contact. By this transfer to the roll, H, the web is re- 10 versed in position so that it presents exteriorly a concave surface and is kept under the same tension and therefore in the same shape as when upon the roll, B. The slight slackening in the tension of the web which 15 would theoretically take place while it is passing across the small space between the rolls B and H may be disregarded, and in any event is prevented by the action of the air blast hereinafter referred to. The trans- 20 fer of the web may be conveniently effected by applying to the inner surface of the web an air blast by any suitable means, as by a blast from an air blower of any usual construction through a main air pipe, G, and 25 thence through a row of pipes, g, located along the desired line of transfer, and having their openings close to the inner surface of the perforated roll, B, by which means the web is blown over, at the proper point, 30 from the roll, B, to the roll, H. In order to enable the web of pulp to be thus transferred without breaking, a portion of the watery content of the web is extracted, whereby it is compacted and 35 strengthened. This may be done by means of air pressure applied thereto through the action of the suction box, C, located within the roll, B, and connected with an air exhaust apparatus. The uniform rate of 40 movement of the web I effect by making up the transfer roll, H, of a series of independent disks or sections, $h, h^1, h^2, \&c.$, rotatably mounted on a fixed shaft, I, shown in section in Fig. 2. These disks may be 45 rotated by contact therewith of a bilge shaped mandrel, M, and the central disks which are in contact with the largest portion of the mandrel will move more rapidly than those successively nearer to the ends of 50 the roll. Hence the portions of the web lying on these sections will move more rapidly than those nearer the edge of the web, and every part of the web will move at substantially the same rate of speed as 55 the corresponding part of the mandrel, M, which in turn revolves at the same speed as the forming roll, B. Hence no straining or breaking of the web will occur when it is transferred to the mandrel to be wound 60 thereon. When the web has been moved to the point where the transfer roll, H, is in contact with the mandrel, M, it is transferred to the mandrel and continues to be wound thereon until a barrel body of the 65 desired thickness is formed, when it is re-

moved from the mandrel. While the barrel body is being formed upon the mandrel I apply pressure thereto, so as to aggregate and consolidate the successive layers, and this pressure may be applied by means of 70 the weight of the mandrel itself. The shaft of the mandrel rests in open bearings, m, m , in which it is free to rise so that space is afforded between the mandrel and the roll, H, for the increasing thickness of the barrel 75 body as successive layers of pulp are deposited thereon, and at the same time it is compressed between the roll, H, and the mandrel by the weight of the mandrel thereon. I do not, however, limit my process to 80 the use of the hereinbefore described apparatus, since any suitable means, such, for example, as the apparatus described in my application for Letters Patent, Serial No. 442,669, filed July 9th, 1908, may be em- 85 ployed for carrying it into effect.

The advantages of my invention will be readily apparent to those skilled in the art; since it provides an article long desired and of great practical utility, that is, a bilge 90 shaped barrel body of paper pulp, strong enough to contain heavy materials, and yet having the lightness and cheapness incident to material of which it is composed.

I do not claim herein the apparatus above 95 described, as I have made the same the subject of a separate application for Letters Patent, Serial No. 355,844, filed Feb. 5th, 1907, of which this application is a division.

What I claim as new and desire to secure 100 by Letters Patent is:

1. The improvement in the art of forming bilged barrel bodies, which consists in lifting a bilge shaped web of paper pulp from a mass thereof, reversing the position of such 105 web so that it shall present exteriorly a concave surface, moving the web forward in this position at uniform speed in each part thereof, the speed being greatest in the central parts, and decreasing therefrom to the 110 edges of the web, and finally again reversing the position of the web and winding it in superposed layers until the desired thickness is attained.

2. The improvement in the art of forming 115 bilged barrel bodies, which consists in lifting a bilge shaped web of paper pulp from a mass thereof, reversing the position of such web, so that it shall present exteriorly a concave surface, moving the web forward in this 120 position, and finally again reversing the position of the web and winding it in superposed layers until the desired thickness is attained.

3. The hereinbefore described improvement 125 in the art of forming bilged barrel bodies which consists in lifting from a mass of paper pulp a web of pulp having the same bilge which it is desired the completed barrel body shall have, moving such web forward in such 130

manner that it shall retain at all points of its progress its original bilged shape and finally depositing it in successive superposed layers to form the barrel body.

5 4. The hereinbefore described improvement in the art of making bilged barrel bodies which consists in lifting from a mass of paper pulp a web of pulp having the same bilge which it is desired the completed 10 barrel body shall have, partially extracting the water from such web, moving such web forward from the point of its formation in such manner that it shall retain at all points of its progress its original bilged 15 shape and finally depositing it in successive superposed layers to form a barrel body.

5. The hereinbefore described improvement in the art of making bilged barrel bodies which consists in lifting from a mass 20 of paper pulp a web of pulp having the same bilge which it is desired the completed barrel body shall have, moving said web forward under tension whereby its bilged shape is maintained, and at a uniform rate of speed 25 in each part thereof, and finally depositing it in successive layers to form a barrel body.

6. The process of making bilged barrel bodies which consists in forming a bilge-shaped web of paper pulp, depositing such 30 web upon a concave surface, and removing the web from such surface to and winding it upon a bilged mandrel.

7. The process of making bilged barrel bodies which consists in forming a bilge-shaped web of paper pulp, continuously de- 35

positing such web upon a concave surface, and continuously transferring the web from such surface to and winding it upon a bilged mandrel.

8. The process of forming vessel bodies 40 having curved sides, which consists in forming a web of paper pulp having the same curve as the side of the article to be formed, depositing such web upon a concave surface having the same curve as the web, and, 45 finally, transferring the web from such surface to and winding it upon a mandrel having the shape of the body to be formed.

9. The hereinbefore described improvement in the art of making bilged barrel 50 bodies, which consists in forming a web of paper pulp having the same bilge which it is desired the completed barrel body shall have, strengthening and compacting the web by partially extracting the water therefrom, 55 bringing the web into such a position that the concave side thereof can be brought into contact with a bilged mandrel, and finally, applying the web to, and winding it upon a bilged mandrel, in successive superposed 60 layers, and under pressure, until the barrel body is formed.

In testimony whereof, I have hereunto subscribed my name, this 27th day of February A. D. 1908.

WILLIAM H. DECKER.
